UNITED STATES PATENT OFFICE.

WILLIAM DOLGE, OF SAN FRANCISCO, CALIFORNIA.

COMBINED SELF-ADDRESSED STATEMENT AND ENVELOP.

1,069,928.

Specification of Letters Patent. Patented Aug. 12, 1913.

Application filed August 10, 1911. Serial No. 643,448.

To all whom it may concern:

Be it known that I, WILLIAM DOLGE, citizen of the United States, residing in the city and county of San Francisco and State of California, have invented new and useful Improvements in Combined Self-Addressed Statements and Envelops, of which the following is a specification.

My invention relates to statements, invoices, notices, etc., designed to be sent through the mail: the invention having been designed especially, as the title implies, as a self-addressing statement for the use of business houses.

In a self addressing statement it is particularly desirable that the address be protected. This is usually done by providing a windowed fold with a transparent sheet having all of its edges pasted to the windowed fold to cover the window. The transparent sheet contracts and expands at a different ratio from the paper of the statement, thus the window covering is crinkled making it difficult to read the address beneath; or it sometimes happens that the transparent sheet is either broken or torn loose from the fold to which it is pasted due to this feature of unequal expansion of the transparent flap and of the paper to which it is pasted. This ratio of unequal expansion and contraction also takes place where a portion of the cover sheet is treated to render it transparent.

The present invention hereinafter specifically described obviates the above specified difficulties by attaching the transparent sheet at one edge only to the windowed fold. This leaves the transparent sheet and the windowed fold free to expand independently, thus enabling the transparent sheet to always lie flat against the address portion.

The invention consists of the parts and the combination and construction of parts as hereinafter more fully described and claimed, having reference to the accompanying drawings, in which—

Figure 1 is a perspective view of the combined statement and envelop. Fig. 2 is a plan view of same in folded form. Fig. 3 is a cross section at Fig. 2.

In Fig. 1 A represents the statement having a portion 2 at the top for the name and address of the customer and sendee and a sealing and cover flap 3 at the bottom, which

has a hole or transparent window portion 4, so arranged that when the statement is folded centrally on itself, the window portion 4 will allow the name and address written on the portion 2 to show through, but otherwise concealing all else written or imprinted on the statement. All that portion of the statement between the addressing portion 2 and the bottom flap 3 is reserved for the statement of account, or any other writing desired. The windowed fold 3 is provided with a sealing tab 5.

In practice, the name of the customer is written in the space 2 and the statement of account filled in, the statement is then folded centrally on itself along a line represented at 6, so as to bring the window opening 4 over the customer's name and address written in space 2. This folded portion is then folded back centrally on itself to reduce the statement to ordinary envelop size. The margin 5 is then gummed to the back of the statement, or an ordinary wire clip or paper fastener slipped over the folded edges of the statement. A 1¢ stamp suffices to carry this through the mails, and yet at the same time there is nothing about the communication to indicate that it is a statement, circular or the like.

The open window 4 in the fold 3 is provided with a transparent sheet 7 which is attached to the windowed fold 3 at one edge only. The line of attachment of the transparent sheet 7 is preferably adjacent the fold line between the windowed fold 3 and the body of the statement. In folding the statement it will be noted that the folding action flattens out the transparent sheet 7 for the reason that the sheet is folded toward the cover portion or windowed fold 3 as will be noted by an inspection of Fig. 3.

The self addressing statement herein described, when folded twice upon itself in the manner shown in the drawings, forms a highly practical labor saving and economical mailable commodity.

Having thus described my invention what I desire to claim is:—

A device of the class described comprising a sheet of paper to be folded along fold lines to form a series of superposed folds, an end fold having a window therein to expose an address portion of said sheet when

the sheet is folded in superposed folds, a
transparent sheet attached to one side of
said windowed fold on a line adjacent to
the fold line of said fold, said transparent
sheet being otherwise free and of a size suf-
ficient to cover said window, and a sealing
flap at the lower end of said windowed fold.

In testimony whereof I have hereunto set
my hand in the presence of two subscribing
witnesses.

WILLIAM DOLGE.
